William G. Mackie Inventor

By Watson E. Coleman

Attorney

UNITED STATES PATENT OFFICE.

WILLIAM G. MACKIE, OF GREEN BAY, WISCONSIN.

DUMPING MECHANISM FOR DUMP SCOWS.

Application filed July 14, 1923. Serial No. 651,522.

To all whom it may concern:

Be it known that I, WILLIAM G. MACKIE, a citizen of the United States, residing at Green Bay, in the county of Brown and State of Wisconsin, have invented certain new and useful Improvements in Dumping Mechanisms for Dump Scows, of which the following is a specification, reference being had to the accompanying drawings.

10 This invention relates to dump scows, and particularly to means for lowering and lifting the dumping gates of scows of this type.

Ordinarily a scow of this character is divided into pockets, as they are called, the 15 bottom of each pocket, which constitutes also a portion of the bottom of the scow, being formed of a pair of hinged gates. These gates are normally supported in a horizontal position and the material carried 20 by the scow is carried on these gates. Then if it is desired to dump the material a pawl and ratchet mechanism or like devices are used for letting loose the gates, which swing down under the weight and discharge the 25 load. Afterwards the pawl and ratchet devices are used for raising the gates.

Where dumping scows are used in carrying and discharging soft semi-liquid or like material such as is dredged from the 30 bottoms of channels and harbors, the dumping operation is a dangerous job for the man performing it.

One of the objects of the present invention is to provide means whereby the dumping 35 gates forming the bottom of the scow may be held raised by hydraulic pressure and may be dumped by air pressure, and in this connection to provide means whereby the bottom doors or gates of any one pocket 40 may be operated separately from the bottom doors or gates of any other pocket.

A further object is to provide means for opening and closing these doors or gates of such character that the speed of the discharge of the contents of the hoppers or 45 pockets may be controlled, which is particularly important when handling soft, semi-liquid or like material.

A still further object is to provide means 50 whereby the doors or gates may be positively locked in their fully closed or partially closed positions by means which cannot be jarred or shaken loose.

Another object is to provide a construction 55 of this character so formed that the doors or gates may be raised or lowered by

one or two operators and without any danger to the operators.

Other objects will appear in the course of the following description.

60 My invention is illustrated in the accompanying drawings, wherein:—

Figure 1 is an elevation of a scow or barge constructed in accordance with my invention, one side wall of the barge being broken 65 away, the transverse bulkheads and bottom of the barge being in section;

Figure 2 is a fragmentary top plan view of the barge, the barge being partly in section;

Figure 3 is a vertical sectional view through one of the cylinders with the corresponding piston depressed;

Figure 4 is a diagrammatic view of my mechanism;

Figure 5 is a transverse section on the line 5—5 of Figure 1.

Referring to the drawings, A designates a scow of ordinary type. This scow, as illustrated, is provided with a medial portion B 80 divided by transverse walls b into a series of pockets or hoppers. The sides C of these hoppers are upwardly and outwardly inclined, these walls C extending from the bottoms of the hoppers upward to the deck beams D. Forming the bottoms of the hoppers are the gates or doors E which are hinged at c, there being two of these gates or doors to each hopper. These gates or doors are both of them engaged at their free 90 ends with flexible elements e. There are a pair of these flexible elements at each pair of doors E. So far I have described a construction which is practically one ordinarily found on all dumping scows.

95 In my construction, I provide within the body of the scow exterior to the hoppers a series of pairs of cylinders 10. There are a pair of cylinders to each pocket. Each cylinder has therein a piston 11 and a piston rod 12 extending upward through the head of the cylinder. These piston rods at their upper ends pass through deck chocks 13 and are connected to flexible elements 14 which 100 pass over the quadrant grooved chocks 15 mounted upon the deck. The flexible elements 14 then pass downward through quadrant grooved chocks 16 and are connected to the flexible members e, as clearly shown 105 in Figure 5. It will thus be obvious that when the pistons in a pair of cylinders are raised, the doors E will be released and will 110

swing downward, discharging the load, and that when the pistons 11 are depressed the doors will be brought upward to a horizontal position to receive a load. I do not wish 5 to be limited to any particular means for supporting the flexible element 14 and guiding it.

Disposed within the scow in any suitable 10 location thereon is a water reservoir or tank 17, and extending longitudinally along the scow is a pipe 18 which is common to all of the cylinders 10. This pipe 18 at intervals between each pair of cylinders has a branch 19 provided with a globe valve 20 and this 15 branch 19 is connected by branches 21 to the upper ends of the pair of cylinders 10. The pipe 18 at one end extends downward, as at 22, into the reservoir or tank 17 and is provided with a valve 23. A branch pipe 24 20 also extends up from the bottom of the reservoir 17 and discharges into the pipe 18.

A pump 25 which I have illustrated diagrammatically and which may be a pump of any suitable construction is connected by a 25 pipe 26 to the pipe 24 and above and below this inlet connection are disposed the check valves 27. These check valves open upwardly. The pump 25 may be of any suitable type, as before stated, and may be operated by any suitable power as, for instance, an ordinary internal combustion engine mounted upon the deck of the scow or in any other suitable position. This pump upon the intake stroke draws water from 30 the tank 17 and upon the discharge stroke forces this water up through the pipe 24 into the pipe 18, or if valve 20 be open it forces water through the pipe 19 into the branches 21 and then into the pair of cylinders 10, forcing the pistons in these cylinders downward to their full extent. If now 35 any countervailing force acts to force the pistons upward, the water will be forced back through the pipes 21, 19 and 18 into the tank or reservoir 17, the upper check valve 27 acting to prevent the water from being forced back into the pump.

Associated with the tank 17 is a compressed air tank 28 which is connected to 40 an air pump 29 and which is provided with the air exhaust valve 30. From the air reservoir 28 extends a pipe 31 having therein a check valve 32, which extends beneath all 45 of the cylinders 10 and is connected by nipples 33 to these cylinders. This air pump may be operated by hand or it may be operated by power.

The operation of the mechanism described 50 is as follows: With the gates or doors E closed, that is in the position shown in Figure 5, if it be desired to dump the load, the air pump is operated or compressed air is taken from the tank 28 and forced through pipe 31 into the lower ends of the cylinders 10. The valves 20 and 23 remain closed

while the compressed air is admitted below the pistons and then these valves are gradually opened after the air pressure below the pistons has attained its maximum. This forces the water in the cylinders 10 out 70 through the pipes 21, 19 and 18 into the tank 17, assuming that the valves 20 and 23 are opened. Until these valves are opened, however, it is obvious that no pressure of air can force the pistons upward. With a 75 constant pressure of air below the pistons and the valves 20 and 23 closed, the pistons will remain in the lower ends of the cylinders and the gates E will remain in a horizontal position. As soon as the valves 20 and 23, however, are opened the pressure of air will force the pistons upward, the water will pass through the pipes 21, 19 and 22 back into the tank 17 and the gates E will be lowered, discharging the cargo. 80

If it be desired to hold the gates at any desired points, the valve 20 is closed and this will prevent any further upward movement of the pistons. If it be desired to control the opening of the gates and to open these gates very slowly, the valves 20 and 23 may be only partially opened, which will only permit a relatively slow passage of the water from the cylinders 10 into the reservoir 17 and thus the gates may be readily controlled. On the other hand, if it be desired to open the gates quickly, the valves 20 and 23 are opened to their full extent, thus permitting the free movement of the pistons within the cylinders 10. After the gates have been opened and the material discharged, if it be desired to lift the gates 95 100 valve 23 is closed and pump 25 is operated which acts to withdraw water from the tank 17 and forces this water up through the pipes 24, 19 and 21 into the upper ends of the pistons. This causes the air to be forced outward through the pipe 31 into the compressed air reservoir 28 and any excess pressure will escape through the valve 30 in this reservoir. As soon as the gates have been fully raised, the valves 20 and 23 are again closed and this will hold the gates 105 110 115 in their closed position.

It will be understood, of course, that I do not wish to be limited to the exact arrangement of parts illustrated nor to any particular form of valves, valve gear, pumps or pump driving mechanism, nor to the particular location of the parts shown. The principle of the invention may be applied in various ways. It will be obvious that the construction is such that it is an easy matter to control the opening and closing of the discharge gates and that there is no danger to the person operating these gates. 120 125

One of the particular advantages of the invention lies in the fact that the gates cannot be jarred or shaken loose, that is so as to swing open, as is the case where rollers 130 135

and ratchets are used for raising, holding and releasing the doors or gates. Furthermore, this apparatus provides for the control of the speed of opening and, therefore, the speed of discharge from the hoppers, which is particularly desirable where these barges or scows are handling soft, semi-liquid mud, silt or like material.

I claim:—

- 10 1. A scow divided to form a plurality of hoppers, a pair of vertically movable dumping gates associated with the lower end of each hopper and means for operating said gates comprising a plurality of cylinders associated with each hopper, a piston in each cylinder, operative connections from the piston to the corresponding pair of gates, a liquid pump, a series of pipes, each pipe being common to the cylinders associated with a hopper, a pipe line operatively connected at intervals to the series of pipes, a manually operable valve in said connection controlling flow from the pipe line into each of the first named pipes, said pipe line being connected to the pump, a check valve in the pipe line preventing return flow to the pump, a liquid tank having a valved connection to the pipe line, the valve being manually operable, a check valve preventing flow from the pump into the tank, a compressed air tank, a pipe line leading therefrom and connected to the several cylinders, and an air pump connected to the air tank, the air tank having an excess pressure valve therein.
- 15 2. A scow having a series of hoppers, a pair of gates for each hopper and means for shifting the gates comprising a plurality of vertical cylinders for each pair of gates, pistons operating therein, flexible connections attached to the pistons passing over the deck of the scow, operative connections from the flexible connections to the corresponding pair of gates, quadrant chocks over which the flexible connections pass, and manually controlled means for forcing fluid into one end or the other of the cylinders to cause the movement of the pistons in one direction to raise the gates or a movement of the pistons in an opposite direction to permit the lowering of the gates.
- 20 3. A scow divided to form a plurality of hoppers, a pair of vertically movable dumping gates associated with the lower end of each hopper and means for operating said gates comprising a plurality of cylinders associated with each hopper, a piston in each cylinder, operative connections from the pis-
- 25
- 30
- 35

ton to the corresponding pair of gates, a liquid pump, a series of pipes, each pipe being common to the cylinders associated with a hopper, a pipe line operatively connected at intervals to the series of pipes, a manually operable valve in said connection controlling flow from the pipe line into each of the first named pipes, said pipe line being connected to the pump, a check valve in the pipe line preventing return flow to the pump, a liquid tank having a valved connection to the pipe line, the valve being manually operable, a check valve preventing flow from the pump into the tank, a compressed air tank, a pipe line leading therefrom and connected to the several cylinders, and an air pump connected to the air tank, the air tank having an excess pressure valve therein.

3. A scow having a series of hoppers, a pair of gates for each hopper and means for shifting the gates comprising a plurality of vertical cylinders for each pair of gates, pistons operating therein, flexible connections attached to the pistons passing over the deck of the scow, operative connections from the flexible connections to the corresponding pair of gates, quadrant chocks over which the flexible connections pass, and manually controlled means for forcing fluid into one end or the other of the cylinders to cause the movement of the pistons in one direction to raise the gates or a movement of the pistons in an opposite direction to permit the lowering of the gates.

In testimony whereof I hereunto affix my signature.

WILLIAM G. MACKIE.
